COMBINED TABLE AND MULTIPLE SEATING UNIT

Truman S. Ziegenfuss, 6940 Los Tilos Road,
Los Angeles, Calif.

Filed Apr. 26, 1961, Ser. No. 64,913

Term of patent 14 years

(Cl. D15—1)

Fig. 1

Fig. 2

Fig. 3

Fig. 4

Fig. 5

FIGURE 1 is a perspective view of a combined table and multiple seating unit embodying my novel design;

FIGURE 2 is an elevational view of the ensemble of FIGURE 1; and

FIGURE 3 is a plan view of the unit shown in FIGURE 1;

FIGURE 4 is a plan view of the article pivoted to an alternate position; and

FIGURE 5 is a plan view of the article of FIGURE 1 pivoted to a 180° angle.

I claim:

The ornamental design for a combined table and multiple seating unit, as shown.
